GASOLINE VAPORIZER

Gustave Hiller, Vancouver, Wash.

Application April 30, 1934, Serial No. 723,107

3 Claims. (Cl. 123—196)

My invention relates to improvements in gasoline vaporizers. The invention primarily comprises a base member and a cap, the two being secured together and forming a vaporizing chamber. A fan is rotatably mounted within the chamber and supported upon a hub. The hub is supported on a hollow stem that communicates with a source of supply of oil vapors that are induced to flow through the stem and through the hub in which the bearing for the rotating member is disposed. The oil vapors flow through the bore of the hollow stem and lubricate the bearing of the rotating member disposed therein.

My invention is adapted for being placed between the carburetor and the intake manifold of an internal combustion engine, and the primary purpose and object of my invention is to promote vaporization of the fuel after the same leaves the carburetor. The hollow stem is adapted for connection to the crank case of the internal combustion engine and for drawing oil and other vapors therefrom, and liberating them in the fuel mixture through my device.

Heretofore, it has been impracticable to place bearings within devices of this kind that would have a long life. Through the use of my new and improved device the bearing is adequately lubricated thereby insuring its longevity. The fan shaped rotating member is preferably made from flat stock. The blades of the fan may be made in the usual and customary manner or they may be formed in a single piece without the separation of the edges of the respective blades thereby to require the passage of all of the vapors through perforations disposed within the respective blades. The blades are inclined to the horizontal and the holes are preferably placed therein when the disc from which the fan is to be made lies in a single plane. Thereafter the blades comprising the fan are offset from the common plane to place the holes out of alignment with the longitudinal center line of the fan. This causes a change of direction in the vapor passing through the holes at high velocity and rotates the fan because of the change in direction of the stream of vapor passing therethrough. This further increases the turbulence in the fuel stream and promotes more complete vaporization thereof.

The primary purpose and object of my invention is to more completely vaporize the fuel to be delivered into the intake manifold of an internal combustion engine. A further object of my invention consists in providing means for lubricating the bearing of the vaporizing member.

A still further object of my invention consists in so constructing the device that it will have a long and useful life and will have practical freedom from mechanical and operating annoyances.

With these and incidental objects in view, the

invention consists in certain novel features of construction and combination of parts, the essential elements of which are set forth in the appended claims, and a preferred form of embodiment of which is hereinafter shown with reference to the drawings which accompany and form a part of this specification.

In the drawings:

Fig. 1 is a side view of the assembled device.

Fig. 2 is a sectional side view of the device illustrated in Fig. 1.

Fig. 3 is a sectional plan view of the assembled device. This view is taken on line 3—3 of Fig. 2, looking in the direction indicated.

Fig. 4 is a sectional plan view of the device taken on line 4—4 of Fig. 2.

Fig. 5 is a side view of an internal combustion engine illustrating one of my new and improved devices in place thereupon.

Fig. 6 is a plan view of a slightly modified form of device. In this view a part of the cap is partly broken away to better illustrate the construction of the same.

Fig. 7 is a sectional side view of the modified form of the device illustrated in Fig. 6.

Fig. 8 is an obverse plan view of the mechanism illustrated in Figs. 6 and 7.

Fig. 9 is a top plan view of the hub and hollow stem on which the rotating fan member is disposed. This view shows the hub and stem removed from the body of the device.

Fig. 10 is a sectional side view of the hub and stem illustrated in Fig. 9.

Fig. 11 is a plan view of an alternative type of fan member.

Fig. 12 is a fragmentary sectional side view of the alternative type of fan illustrated in Fig. 11.

Like reference characters refer to like parts throughout the several views.

On motors of the larger sizes where ample installation space is available, the device is made as illustrated in Figs. 1 to 4 inclusive. When so made the device is comprised of a base 1. A flange 2 is formed integral with the base and fastening holes 3 extend therethrough to facilitate attachment to a companion flange 4 as disposed upon a carburetor 5.

A top 6 is provided having a flange 7 disposed upon one end and a flange 8 is disposed upon the opposite end. The flange 8 is adapted for attachment to a companion flange 9 formed integral with intake manifold 10. The base 1 has a flange 11 disposed upon its top end and complementary to the flange 7 and is secured thereto by suitable fastening screws 12.

A gasket 13 is placed between the complementary flanges 7 and 11 to maintain a gas tight relationship therebetween. A cross support 14 is formed integral with the base 1. A hub 15 is disposed within the top of the cross support 60

and a suitable anti-friction bearing 16 is disposed therewithin. A passageway 17 extends longitudinally of one end of the cross support 14 and a threaded connection 18 communicates with the passageway 17 at its one end and with a piping connection 19 at its other end. The piping connection 19 leads to crank case 20 of internal combustion engine 21.

A reservoir 22 is disposed within the hub and 10 is in open communication with the passageway 17. A fan 23 is journaled in the anti-friction bearing 16. The fan as illustrated in Figs. 2 to 4 inclusive is comprised of a plurality of spaced blades 24. The blades have perforated spaced 15 holes 25 disposed therein and extended therethrough. The holes are formed within the flat sheet and are therefore normal to the surface of the sheet from which the fan is made. Thereafter the blades are placed at an angle to necessitate the change of direction of the carbureted 20 fuel passing therethrough that gives the same greater turbulence and aids in the further vaporization of the fuel.

In Figs. 6 to 12 inclusive I have shown a modified form of device for use especially in installations where space is restricted. In this form base 26 and top 27 are preferably made of non-corrodible metal. The base has an inwardly sloping wall 28 that is inclined substantially 54 degrees to the horizontal and the top 27 has an inwardly sloping side wall 29 that is inclined to the horizontal substantially 43 degrees. The base has a side wall 30 that is disposed at right angles to the end walls 31 and 32 of the respective top and base members. This forms an opening transversely through the base and top that has similar terminal diameters and forms a bowl shaped space within which a fan 33 is rotatably disposed.

40 A hollow stem 34 extends transversely of the base and has a hub 35 disposed upon its inner end, the center of which is preferably placed to coincide with the longitudinal center line normal to the surfaces of the respective top and base members.

An anti-friction bearing 36 is disposed within the hub and carries a spindle 37 to which the fan 33 is secured by suitable fastening means as through the use of a nut 38. The hollow stem 50 34 is placed in open communication with a source of oil vapor as the crank case of an internal combustion engine and in the normal operation of the engine the oil vapors are drawn through the anti-friction bearing 36 to lubricate it. An 55 alternative fan structure is disclosed in Figs. 11 and 12. In this type, each of the vanes of the fan has spaced holes 39 extending therethrough. These holes are preferably placed within the disc prior to the formation of the vanes. Thereafter 60 the vanes are offset as illustrated in Fig. 12 and the adjacent edges of the respective vanes are secured together by webs 40. This forces practically all of the carbureted material to flow through the spaced holes, and as in the forming 65 of the vanes the holes are inclined at an angle to the axis of the fan, the material passing therethrough at high velocity causes the fan to rotate, increasing the turbulence in the vaporized fuel passing therethrough; and the holes being 70 small further vaporizes the carbureted material and delivers the completely carbureted material to the intake manifold of the engine. The oil bearing crank case vapor flowing upward through the hub in which the rotating member is jour-

naled maintains the bearing in a lubricated condition.

The cap is secured to the base as by suitable fastening screws 41 and 42 and the assembly is secured between the flanges of the carburetor and the intake manifold by suitable fastening means passing through holes 43 and 44 that are disposed longitudinally of the assembly. A suitable piping connection not here shown connects opening 45 disposed within the base to the crank case 10 of the internal combustion engine.

While the form of mechanism herein shown and described is admirably adapted to fulfill the objects primarily stated, it is to be understood that it is not intended to confine the invention 15 to the embodiment herein shown and described, as it is susceptible of embodiment in various forms, all coming within the scope of the claims which follow.

What I claim is:

1. In a device of the class described, the combination with an internal combustion engine, of a base body element, a cross support disposed transversely of the base body element, a hub disposed centrally of the cross support, the cross support being provided with a communicating passageway between the hub and the outside of the body element, a fan rotatably journaled within the hub, said fan having perforations extending through the vanes, communicating means disposed between the passageway and the crank case of the internal combustion engine for conducting lubricant vapor from the crank case to lubricate the fan bearing, a top removably secured to the base body element, means for securing the base body element to a carburetor and for securing the top to the intake manifold of the engine.

2. In a device of the class described, the combination with an internal combustion engine, of a split fan housing that forms a fan chamber having a central cylindrical inner wall and converging into a frusto-conical shaped wall at each end of the central cylindrical wall, said housing being secured between the intake manifold and the carburetor of the engine, a hub disposed centrally of the housing and having an anti-friction bearing disposed therein, a passage disposed longitudinally of the hub supporting bracket, communicating means disposed between the 40 passage and the crank case of the internal combustion engine for conducting lubricant vapor to said bearing, a fan journaled within the bearing, said fan having a plurality of spaced perforations disposed in each of its vanes.

3. In a device of the class described, the combination with an internal combustion engine, of a split fan housing that forms a fan chamber having a central cylindrical inner wall and converging into a frusto-conical shaped wall at each 60 end of the central cylindrical wall, said housing being secured between the intake manifold and the carburetor of the engine, a hub disposed centrally of the housing and having an anti-friction bearing disposed therein, a passage disposed longitudinally of the hub supporting bracket, communicating means disposed between the 65 passage and the crank case of the internal combustion engine for conducting lubricant vapor to said bearing, a fan journaled within the bearing, the adjacent edges of the vanes of the fan being secured together by a connecting web, and perforations extending through each of the vanes.

GUSTAVE HILLER.
